UNITED STATES PATENT OFFICE.

GEORGE H. LEIGH AND VERNIE R. LEIGH, OF DREWRYVILLE, VIRGINIA.

GLASS BURIAL-CASKET.

1,180,054.

Specification of Letters Patent. Patented Apr. 18, 1916.

Application filed April 1, 1915. Serial No. 18,529.

To all whom it may concern:

Be it known that we, GEORGE H. LEIGH and VERNIE R. LEIGH, citizens of the United States, residing at Drewryville, in the county of Southampton and State of Virginia, have invented certain new and useful Improvements in Glass Burial-Caskets; and we hereby declare that the following is a full, clear, and exact description thereof, reference being had to the accompanying drawings, which form part of this specification.

This invention relates to burial caskets, and more particularly to caskets made of glass and hermetically sealed.

The main object of the invention is to provide an improved casket of the character referred to adapted to be readily locked and hermetically sealed and which shall possess great strength and durability combined with simplicity and efficiency in practical use.

The invention will first be hereinafter more particularly described, with reference to the accompanying drawings, which form a part of this specification, and then pointed out in the claims at the end of the description.

In said drawings, Figure 1 represents a perspective view of a burial casket embodying our invention; Fig. 2 is a vertical longitudinal sectional elevation of the same.

Referring to said drawings, in which the same reference letters are used to denote corresponding parts in different views, the letter A denotes the body of the casket, which may be made of glass by any of the well known methods of glass-making and of any desired size and form. As shown, it is of oblong box-like form, rectangular in cross section, and may be of any desired dimensions, according to the wishes of the manufacturer or the requirements in practical use. At one end of the casket there is an opening for the insertion of the corpse, said opening being preferably circular in form and of such size that the circle described by the opening will touch the top and bottom walls of the casket, so that the opening at top and bottom will be flush with the interior surface of the casket. The circular opening is preferably formed so that its walls taper inwardly to receive a correspondingly tapered cover. In other words, the circular opening is bounded by inclined walls and the cover is of circular form and has inclined walls to fit the inclined walls of the end. The inner surface of the opening

may be given a ground glass finish to adapt it to receive the lid or cover B, which may consist of molded or blown glass of such size and shape as to exactly fit within the circular opening, and may likewise have a ground glass finish so as to make the device as nearly air-tight as possible.

In the process of molding the casket may be formed with several transverse shallow grooves extending entirely around the same to receive metallic bands C, fitting snugly in said grooves with their outer surfaces flush with the outer surface of the casket. The casket is also provided on opposite sides thereof with longitudinal shallow grooves in which are fitted metallic bands D, to which may be attached suitable handles E, preferably coincident with the transverse bands C which pass over and hold the bands D firmly in place. The meeting ends of the bands C may be welded together, or overlapped and secured together by bolts or rivets as desired, and it may also be desirable to secure both the longitudinal and transverse bands within the recesses or grooves by cement or other adhesive substance.

The lid or cover has integral lugs or projections b adapted to engage projecting ears or lugs a on the end of the casket, and integral therewith, for securing and locking the cover firmly to its seat; said lugs a having inturned flanges a¹, the inner sides of which are inclined to provide cam surfaces for contact with the lugs on the cover so that as the cover is turned it will be forced firmly to its seat, and thereupon the casket may be hermetically sealed, and to this end an annular groove a² is formed on the inner side of the projecting end of the casket so that a part of the material used in hermetically sealing the casket may enter the groove and insure a perfect seal, and also prevent the seal from being broken.

To facilitate the insertion of the corpse within the casket, we provide a receiving-board F, which may consist of a plurality of strips of metal or other suitable material hinged together at their edges and of such length and width as to provide a board of the width of the interior of the casket, thus forming a foldable false bottom that may be slid in and out as desired through the circular opening. To facilitate handling it may be provided with loops at each side (not shown) and a loop f³ at the front

formed of fabric or other suitable flexible material to provide suitable handles on opposite sides and at the front end, as shown. The surface of the body of the casket has 5 preferably a single groove extending longitudinally thereof on a median line at each side and a transverse groove at each end and also about midway of its length, the longitudinal grooves uniting with the end 10 grooves, and the steel bands fitting in the end grooves preferably overlie the longitudinal bands and hold them in place; but a greater or less number of grooves and bands may be used and any suitable fixtures 15 for handles may be secured to the longitudinal plates on each side for carrying purposes.

Having thus described our invention, what we claim as new and desire to secure 20 by Letters Patent of the United States is:

1. A glass burial casket comprising an oblong box-like integral glass body having a circular opening therein bounded by inclined walls at one end and a cover for said 25 end of circular form and having inclined walls to fit the inclined walls of the end and having laterally projecting lugs thereon; said body having at its open end integral flanges having inclined cam-surfaces engaging 30 said lugs so that when said cover is turned it will be forced tightly to its seat.

2. A glass burial casket comprising an oblong box-like integral glass body having a circular opening therein bounded by inclined walls at one end and a cover for said 35 end of circular form and having inclined walls to fit the inclined walls of the end and having laterally projecting lugs thereon; said body having integral end flanges with cam surfaces engaging said lugs so that 40 when said cover is turned it will be forced tightly to its seat, and also having beside said circular opening an interior annular

groove to receive material used for hermetically sealing the casket so as to insure a perfect seal and prevent it from being broken. 45

3. A burial casket comprising an oblong box-like glass body having at one end an opening for the insertion of the corpse and a removable cover for said opening together 50 with means for locking the cover to its seat; said body also having exterior transverse grooves with metal bands fitted therein and longitudinal grooves with metal bands fitted therein underlying said transverse bands; 55 said longitudinal bands having suitable handles thereon at each side of the casket for carrying purposes.

4. A burial casket comprising an oblong hollow glass body open at one end and having exterior transverse grooves and longitudinal grooves in its sides, metal bands seated in said transverse grooves encircling said body, and metal bands seated in said longitudinal grooves underlying the transverse bands and having handles thereon for carrying purposes, and a detachable cover for said open end with provision for hermetically sealing the same. 60 65

5. A glass burial casket having a circular 70 opening in one end bounded by inclined walls, a circular cover closely fitting said opening and having inclined walls to fit the inclined walls of the end, and an interior annular groove beside the outer wall of the 75 cover adapted to receive material for hermetically sealing the same.

In testimony that we claim the foregoing as our own, we affix our signatures in presence of two witnesses.
